RECOVERY OF ISOPRENE FROM HYDRO-CARBON MIXTURES COMPRISING SAME AND PIPERYLENE

Stephen C. Stowe, Midland, Mich., assignor to The Dow Chemical Company, Midland, Mich., a corporation of Michigan

No Drawing. Application December 4, 1942,
Serial No. 467,899

1 Claim. (Cl. 260—681.5)

This invention concerns a method of recovering isoprene of good purity from hydrocarbon mixtures comprising the same and its isomer, piperylene. It particularly concerns the recovery of substantially pure isoprene from a mixture of the sulphones of isoprene and piperylene.

In industrial processes for the pyrolysis of petroleum fractions and other hydrocarbon starting materials, low boiling mixtures comprising conjugated diolefines are produced in large quantities. The mixtures thus produced are usually complex. For instance, cracked-oil gas, a readily available source of diolefines, usually comprises paraffinic hydrocarbons ranging from methane to hexane, olefines ranging from ethylene to hexylene, diolefines such as butadiene, isoprene, piperylene, etc., and acetylenic hydrocarbons such as acetylene, methyl-acetylene, ethyl-acetylene, and vinyl-acetylene, etc.

Such complex hydrocarbon mixture may be fractionally distilled to obtain fractions consisting for the most part of hydrocarbons having the same number of carbon atoms in the molecule, e. g. a C₄ fraction consisting largely of hydrocarbons such as butanes, butylenes, butadiene, and acetylenic hydrocarbons containing from 3 to 4 carbon atoms in the molecule and a C₅ fraction consisting largely of pentanes, amylenes, the conjugated diolefines isoprene and piperylene, and acetylenic hydrocarbons. Ways are known for separating conjugated diolefines from other kinds of hydrocarbons, and butadiene, which is the only conjugated diolefine in the C₄ fraction, may be isolated from the C₄ fraction in known ways. However, no method is known whereby either of the individual diolefines, isoprene and piperylene, may satisfactorily be recovered in pure form from the C₅ fraction.

It is an object of this invention to provide a practical method whereby the major portion of the isoprene in a hydrocarbon mixture comprising the same and piperylene may readily be separated in substantially pure form.

It is reported in the literature that the crystalline monomeric sulphones of butadiene and isoprene each decompose at 120° C. to form a gaseous mixture of sulphur dioxide and the diolefine. I have observed that this teaching is not correct and that the decomposition may occur at considerably lower temperatures. A reduction in the pressure on the system as a whole, or a reduction in the partial pressure of either reaction product, has the effect of increasing the rate of decomposition.

I have further found that when a mixture of

the sulphones of isoprene and piperylene, such as may be obtained by treating a mixture comprising said diolefines with sulphur dioxide, is heated, both sulphones undergo decomposition at the same temperatures, but that the rate of decomposition of the sulphone of piperylene far exceeds that of the sulphone of isoprene. By heating the mixture of isomeric sulphones at a moderate reaction temperature, the sulphone of piperylene may be decomposed to evolve sulphur dioxide and piperylene, together with some isoprene, leaving the major portion of the sulphone of isoprene substantially pure. The residual sulphone of isoprene may thereafter be thermally decomposed to recover the isoprene in a form substantially free of other hydrocarbons.

In practice of the invention, a hydrocarbon mixture comprising isoprene and piperylene is reacted in liquid phase with sulphur dioxide to form the sulphones of the diolefines. Any hydrocarbons other than conjugated diolefines, e. g. paraffinic hydrocarbons, olefines or acetylenes such as pentanes, amylenes, or pentynes, etc., remain unreacted and are readily separated from the sulphone products. Procedures for carrying out the reaction to form sulphones of conjugated diolefines and for separating the sulphone products from unreacted hydrocarbons and sulphur dioxide are well known and do not require detailed description. Cracked-oil gas usually contains small amounts of isoprene and piperylene, each in a relative proportion corresponding to at least 20 per cent of the combined weight of the two compounds, and the sulphones are, of course, obtained in similar proportions.

The mixture of the sulphone products is heated sufficiently to cause a smooth and fairly rapid, but not sudden, decomposition of the sulphones with evolution of the resultant mixture of sulphur dioxide, piperylene and isoprene, whereby the sulphone of piperylene is decomposed far more rapidly than is that of isoprene and is removed before more than a minor amount of the sulphone of isoprene is destroyed. It is probable that the sulphone of piperylene decomposes more rapidly than that of isoprene regardless of the temperature employed and the step of decomposing and removing the sulphone of piperylene to leave the major portion of the sulphone of isoprene in purified form may be carried out at temperatures as high as 130° C., or possibly even higher. However, withdrawal of the piperylene from the reaction mixture before an excessive amount of the sulphone of isoprene is decomposed becomes more difficult as the reaction temperature is raised.

For this reason, the step of decomposing and removing the sulphone of piperylene is usually carried out at temperatures below 120° C., and preferably between 70° and 115° C.

The decomposition may be carried out in the presence or absence of solvents or liquid diluents such as water, kerosene, or benzene, etc., and at any desired pressure, e. g. at atmospheric, super-atmospheric or at subatmospheric pressure, and the temperature at which the decomposition may most advantageously be carried out is dependent in part upon the other conditions employed. By carrying the decomposition out in the presence of a diluent or by reducing the pressure on the system the rate of decomposition is increased and satisfactorily rapid decomposition may be obtained at a temperature lower than would otherwise be required.

In practice, the mixture of sulphones is usually heated to a temperature sufficient to cause a fairly rapid evolution of the decomposition products and the temperature is gradually raised as necessary for continued reaction at a satisfactory rate. Operation in this manner is continued until substantially all of the sulphone of piperylene has been removed. The residual sulphone of isoprene is thereafter decomposed in the usual manner, e. g. by heating at 120° C. or above, to obtain a mixture of sulphur dioxide and isoprene. This mixture is scrubbed with water, or a dilute aqueous alkali solution, or treated in other usual ways to separate the sulphur dioxide and isoprene, whereby the latter is obtained in purified form. The yield of purified isoprene from the foregoing steps depends to some extent, of course, upon the proportion of isoprene in the initial hydrocarbon fraction, but is usually more than 50 per cent of theoretical.

The yield may be improved by collecting the mixture of sulphur dioxide, piperylene and isoprene which is evolved during the step of thermally decomposing the sulphone of piperylene, treating the mixture to remove the sulphur dioxide, and fractionally distilling the remaining mixture of piperylene and isoprene to concentrate the latter. Although, it is difficult, if not impossible, to separate either isoprene or piperylene from a cracked-oil gas fraction by fractional distillation, a mixture of these diolefines alone, which contains only a small amount of isoprene, may readily be distilled to obtain a first fraction of distillate containing the major part of the isoprene in a relatively concentrated form, e. g. in a concentration of 30 per cent by weight or higher. This fraction may be returned to the step for the formation of the sulphones of isoprene and piperylene and the mixture of sulphones may be treated as hereinbefore described to again recover the major portion of the isoprene in purified form.

The process as just described may be practiced in batchwise or in continuous manner, as desired. By continuously feeding a hydrocarbon mixture comprising isoprene and piperylene to the process and concentrating and recycling the isoprene evolved during the step of selectively decomposing the sulphone of piperylene, 90 per cent or more of the isoprene may be recovered as the substantially pure compound.

The following example describes one way in which the invention has been practiced, but is not to be construed as limiting the invention.

Example

The sulphones of isoprene and piperylene were prepared by treating a liquefied cracked-oil gas

fraction, which was rich in isoprene and piperylene but which also contained other hydrocarbons of unknown identity, with liquid sulphur dioxide in amount corresponding to about 2.5 moles of sulphur dioxide per mole of the diolefine, and permitting the liquid mixture to stand under pressure in an autoclave at room temperature for 24 hours. The pressure was then released and the mixture was gradually warmed to 60° C., whereby the excess sulphur dioxide and unreacted hydrocarbons were vaporized from the sulphone products. Thereafter, the temperature was gradually raised. Decomposition of the sulphones became noticeable at 70° C. and occurred smoothly and quite rapidly at 80° C. The temperature was raised further as necessary in order to maintain a fairly uniform evolution of vapors of the decomposition products, i. e. sulphur dioxide, piperylene and isoprene. The products were collected in successive fractions and each fraction was freed of sulphur dioxide by extraction with a dilute aqueous sodium hydroxide solution. The remaining hydrocarbons, which were in liquefied form, are referred to in the following table as the "hydrocarbon condensate." Each hydrocarbon condensate was analyzed by a fractional distillation method to determine the proportions of isoprene and piperylene therein. The following table gives the decomposition temperatures at which the successive fractions of the products were formed. It also gives the volume of the hydrocarbon condensate obtained by removing the sulphur dioxide from each fraction and the composition of each hydrocarbon condensate in terms of the per cent by volume of isoprene, of piperylene and of residue obtained or identified in the distillation.

Table

Fraction No.	Decomp. temp., ° C.	Hydrocarbon condensate, c. c.	Distillation of condensate		
			Isoprene, per cent by vol.	Piperylene, per cent by vol.	Residue, per cent by vol.
45					
1	70-90	55.0	6.4	40.0	53.6
2	90-102	134.0	9.8	63.7	26.5
3	102-105	129.0	21.0	67.6	11.4
4	105-113	97.5	18.0	67.3	14.7
5	113-120	157.5	60.7	29.1	10.2
6	120-123	91.0	82.4	None	17.6
7	124	104.5	90.5	None	9.5
8	124-137	134.0	88.9	None	11.1

It is probable that the residues which were obtained when the hydrocarbon condensates were distilled consisted in part of the diolefines held up as inventory in the distilling column and in part of polymers of the diolefines, and that the diolefine-content of the hydrocarbon condensates is somewhat higher than indicated in the above table. For instance, upon distillation of the hydrocarbon condensates corresponding to fractions 6, 7, and 8 there were obtained 75 c. c., 94.5 c. c., and 119 c. c., respectively, of isoprene of high purity. It is probable that the residues, in these instances, comprised isoprene retained in the distilling column and a small amount of polymerized isoprene. Approximately 65 per cent of the isoprene initially present in the hydrocarbon mixture was recovered as the pure compound.

Other modes of applying the principle of the invention may be employed instead of those explained, change being made as regards the method herein disclosed, provided the step or steps stated by the following claim or the equivalent of such stated step or steps be employed.

I therefore particularly point out and distinctly claim as my invention:

In a method for separating isoprene from a hydrocarbon mixture comprising isoprene and piperlylene, the steps of treating the mixture in liquid phase with sulphur dioxide to form sulphones of the isoprene and piperlylene, vaporizing unreacted hydrocarbons and sulphur dioxide from the sulphones, heating the mixture of sulphones to a decomposition temperature between 70° and 120° C., whereby the sulphones are gradually decomposed with evolution of a vapor mixture of sulphur dioxide, piperlylene and isoprene, continuing heating at temperatures between 70° and 120° C., until the vapors being evolved are substantially free of piperlylene and a substantial portion of the sulphone of isoprene remains, free-

ing the evolved mixture of sulphur dioxide, distilling the resultant mixture of piperlylene and isoprene which remains after removal of the sulphur dioxide to obtain a fraction of distillate containing the major portion of the isoprene in relatively concentrated form together with some piperlylene, recycling this fraction through the foregoing steps for the formation of the sulphones and for the decomposition of the sulphone of piperlylene to leave, as a residue from the latter reaction, a large part of the sulphone of isoprene in purified form, heating the purified sulphone of isoprene to decompose the same and form a mixture of sulphur dioxide and isoprene, and separating the sulphur dioxide and isoprene to recover the latter as the purified compound.

STEPHEN C. STOWE.
